SUPERREGENERATIVE RECEIVER

Ralph W. George, Riverhead, N. Y., assignor to
 Radio Corporation of America, a corporation
 of Delaware

Application January 28, 1932, Serial No. 589,392

5 Claims. (Cl. 250—20)

This invention relates to regenerative receiving systems, and more particularly to an improved type of super-regenerative receiving circuit.

In United States Patent No. 1,982,694, granted December 4, 1934, to Walter Van B. Roberts, there is disclosed a method of securing high amplification in a super-regenerative system without building up sustained oscillations. Briefly, the method disclosed in the aforementioned application comprises periodically reversing the phase of the feed-back in the system for rapidly quenching radio frequency oscillations during the damping period. The particular embodiment disclosed therein consists of a pair of space discharge devices, one of the devices intermittently functioning as an oscillator generator, the other device intermittently and alternately with the first device acting to quench oscillations prior to the instant when oscillations built up by the oscillator generator would otherwise attain an undesirable amplitude.

Reference is also made to United States Patent No. 1,948,315, granted February 20, 1934 to Walter Van B. Roberts, wherein there are disclosed various embodiments for producing super-regeneration in a receiving system including a pair of oppositely connected space discharge devices, the basic method employed in each of these embodiments consisting of applying simultaneously both signal energy and a low frequency interrupting voltage in a differential manner to the devices, the common output circuit being coupled to the common input circuit of the devices. It is pointed out in this patent, *supra*, that the embodiments disclosed therein can be considered as balanced modulator circuits, wherein a signal collecting circuit and a relatively low frequency modulating voltage source are provided with additional means for feeding back to the signal circuit the side bands at radio frequencies produced by modulation of signal voltages. In particular, the patentee discloses a super-regenerative arrangement wherein a source of interrupting frequency is coupled directly across the input of a pair of oppositely connected space discharge devices, a common feed-back reactance in the common output circuit of the device being utilized to couple the output circuit to reactances in the common input circuit of the devices. While various advantages are stated as being secured by means of the aforementioned super-regenerative embodiments, further experimentation and development of this type of super-regenerative circuit has resulted in additional advantages.

It is an object of the present invention to pro-

vide a super-regenerative receiving system wherein in the low frequency circuits can have no possible detrimental effect on the high frequency circuits, and this is attained by coupling the relatively low frequency quenching interrupter to the cathodes of the electron discharge device.

An advantage of the present invention is that the whole arrangement of parts can be made relatively simple, and the symmetry and efficiency of the grid circuit maintained more easily than heretofore possible.

A further advantage of this invention is that the source of interrupting frequency may be placed in a remote and more suitable location than immediately adjacent the main portion of the super-regenerative circuit.

The invention is described in more detail in the following description which is accompanied by a single drawing, wherein there is shown a super-regenerative receiving circuit embodying the principles of the present invention. Essentially, the circuit comprises a pair of electron discharge devices 11 and 12 of the indirect heater type which have their respective corresponding electrodes connected together, and a source of quenching frequency current 18 coupled to the cathodes thereof. Although the indirect heater type of tube is shown in the drawing, it is to be understood, of course, that the showing is merely for purposes of illustration since any other suitable electron discharge tube, such as the directly heated three element tube, the tetrode or pentode may be used instead, if desired.

The incoming high frequency signals are received over input coil 10 which is coupled to the tubes 11 and 12 through resonant circuit 13, 14 tuned to the input signal frequency. The electron discharge devices 11 and 12 have connected to their anode circuits a feed-back coil 15 which is coupled to the grids of the tubes through inductance coil 13. Positive potential is applied to the anodes of the tubes, which are directly connected together, from a source 20. The positive terminal of source 20 is connected in series with feed-back coil 15 through a signal utilization means 21, the latter comprising, for example, a pair of headphones. The fixed condensers 16, 17 and 22 are radio frequency by-pass condensers. A keying or relatively low frequency quenching oscillator 18 is shown coupled to the cathodes 19, 19 of the tubes through coils 23, 24 for varying periodically the potential of the cathodes with respect to the grids.

Coils 13 and 23 are connected at their center points to ground and battery respectively and

thus permit the application simultaneously of both signal energy and the relatively low frequency interrupting voltage to devices 11 and 12 in a differential manner.

5 Quenching frequency oscillator 18 preferably functions at an audible frequency of about 8000 cycles per second. In practice it has been found that a wide range of quenching frequencies may be used satisfactorily. For example, when this 10 super-regenerative circuit is employed with an ultra short wave receiving circuit of the type described in my United States Patent No. 2,011,942, granted August 20, 1935, a quenching frequency of the order of 25 kilocycles may be used with 15 excellent results.

15 Signal input circuit 10 may be connected directly to an antenna circuit or coupled to the output of a stage of amplification disposed between the antenna and the input circuit of tubes 20 11 and 12. Of course, if desired, a source of high intermediate frequency current produced by another receiver may be placed between the antenna and the signal input circuit of the super-regenerative circuit. In other words, it is to be 25 clearly understood that the circuit shown in the drawing lends itself readily to amplification of radio frequencies regardless of the source of such 30 radio frequencies.

30 The manner of coupling the quenching oscillator 18 to the cathodes, as herein described, instead of to the control electrodes of the tubes, as has been done heretofore, has the advantage of giving simplicity and symmetry to the circuit and at the same time maintaining the efficiency of 35 the grid circuit. Inasmuch as the potentials between the grids and cathodes are keyed or changed by and at the quenching frequency, the operation of the circuit is equivalent to that when the relatively low quenching frequency is coupled 40 directly to the grid circuit, which is described in detail in the aforementioned Roberts' Patent No. 1,948,315.

45 It is to be clearly understood that this invention is not limited to a circuit employing only two tubes, but may be applied to any super-regenerative circuit. Further, this particular arrangement may be advantageously used in modulating transmitters and coupling to amplifiers. In such arrangements, if desired, the symmetry 50 of the circuit may be maintained by connecting suitable impedance matching devices in the cath-

ode circuits without affecting the plate or grid circuits.

I claim:

1. In combination, in a super-regenerative receiver, a pair of electron discharge tubes each 5 having a cathode, anode, and control electrode, means for connecting the corresponding respective electrodes together, an input circuit connected to said control electrodes in opposite senses, a common output circuit connected to the anodes 10 of said tubes and coupled to said input circuit, a source of relatively low frequency current, and means for differentially coupling said source to the cathodes of said tubes.

15 2. A super-regenerative receiver circuit comprising a pair of electron discharge devices each having an anode, grid, an electron emitting electrode, and a heating element, means for connecting the corresponding respective electrodes of said devices together, a source of direct current heating energy for the heating elements of said devices, a source of relatively low frequency current, and means for differentially coupling said last source to the electron emitting electrodes 20 of said devices.

25 3. A super-regenerative receiver circuit comprising an indirectly heated electron discharge device having a plurality of electrodes including an electron heating element and an electron emitting element, input and output circuits for said 30 devices coupled together, a source of direct current heating energy for the heating element of said electron discharge device, a source of periodic interrupting current, and means for coupling said last source to the electron emitting element 35 of said device.

40 4. A super-regenerative receiver comprising a pair of electron discharge devices having anode, cathode and control electrodes, means for connecting the respective corresponding electrodes of said devices together, and means for differentially exciting the cathodes of said pair of devices comprising a source of interrupting current.

45 5. A super-regenerative receiver circuit comprising a pair of indirect cathode heater-type 45 tubes having anode, grid, heating and electron emitting elements, means for connecting said corresponding elements together, and means for differentially exciting the electron emitting elements of said pair of tubes.

RALPH W. GEORGE.
